LUGGAGE

Samuel J. Holtzman, 8201 Symphony Drive,
Baltimore 8, Md.
Filed Nov. 28, 1960, Ser. No. 72,006
19 Claims. (Cl. 190—51)

The invention relates to luggage, and is more particularly directed to improvements in dividers or partitions for suit cases, Gladstone bags, hat boxes, or similar luggage cases or containers.

Conventional luggage case partitions are in the form of a supporting member of cardboard, or a length of metal wire bent into a supporting edge, which is covered with a fabric. The partition is hinged to one of the case halves and is provided with a pair of spaced metal eyelets near its free edge to receive similarly spaced turnbutton elements mounted on the cooperating case half to thereby permit retention of the packed goods. The partition may be provided with pockets sewn to the fabric covering to permit the storage of small articles.

Not infrequently, luggage is unevenly packed and overloaded, whereupon the conventional partitions do not well retain their original peripheral outline and flat, planar condition. The partition's peripheral edge conforms less to the radii of the case's internal outline than it did when new. Moreover, it has been difficult to make a partition which initially conforms closely to the often complex radii of the case with which it is assembled.

Also, where the partitions of known structure are provided with pockets to receive small objects, and in the event that something is spilled in a pocket which soils the fabric thereof, one cannot thoroughly clean the fabric, because the pocket cannot be separated from the partition.

In accordance with the invention, a luggage case partition is provided which is strong and durable. The partition conforms to the contents of the case which may be both overloaded and unevenly distributed. Nevertheless, though twisted and bent out of its normally flat, single planar condition by a nonuniformly distributed overload, the partition readily returns to its normal condition and conforms closely to the outline of the inner periphery of the case when the compressive and twisting stresses thereon are removed, thereby suitably accommodating another load of goods which may be differently distributed in the case. The partition of the invention is precisely dimensioned and constructed so that initially, and after extended and overloading use, it conforms to the complex radii of the inner periphery of the case with which it is cooperatively related.

The partition of the invention is of a unitary construction; it is made in a single operation, thereby eliminating the necessity to stock and assemble several parts. The partition possesses integrally formed hinge means, thereby eliminating the necessity of sewing or otherwise permanently connecting the partition to the case. Also, the partition possesses integrally formed means for cooperation with the turnbuttons, thereby eliminating the usual metal eyelets and the operation of attaching them to the partition, together with the cost of such components and the expense of the attaching operation.

Moreover, the partition of the invention is not readily soilable, and if soiled, it may be cleaned by simply wiping with a cloth. In the preferred embodiment of the invention, the partition is constructed to permit a fabric pocket or pockets to be separably connected thereto so that when the pocket material is soiled it may be removed for a thorough cleaning, and then readily reassembled with the partition.

2

These, and other purposes and advantages of the invention will be apparent from the following detailed description, taken in conjunction with the drawings illustrating a preferred embodiment of the invention, in which:

5 FIG. 1 is a perspective view, partly broken away and in section, showing a luggage case provided with a partition made in accordance with the invention;

FIG. 2 is a front elevational view of the partition, the specific embodiment herein illustrated including means for removably supporting pockets, this view showing the pockets assembled with the partition;

FIG. 3 is a vertical section taken approximately in the plane of line 3—3 of FIG. 2;

15 FIG. 4 is a view similar to FIG. 2, this view however, showing the partition with the pockets removed;

FIG. 5 is a vertical cross-sectional view illustrating the manner in which the partition is hingedly connected to the case;

FIG. 6 shows the hinged connection between partition and case when viewing FIG. 5 from the right side thereof;

FIG. 7 is a fragmentary, side elevational view, partly in section, showing the relationship of the partition with respect to a turnbutton;

25 FIG. 8 shows the relationship of turnbutton and partition when viewing the right side of FIG. 7, this view showing the turnbutton in its closed or holding position;

FIG. 9 is a perspective view, partly broken away and in section, showing a pocket member suitable for assembly with the partition shown in FIG. 4;

30 FIG. 10 is a perspective view of another form of pocket member suitable for assembly with the partition shown in FIG. 4;

FIG. 11 is a vertical cross-sectional view taken approximately in the plane of line 11—11 of FIG. 4; and

35 FIG. 12 is an end view of the partition's hinge means looking in the direction of the arrows 12—12 of FIG. 4.

A luggage partition made in accordance with the invention comprises a unitary grille- or lattice-like member of plastic material. The grille-like member preferably is made by molding a thermoplastic composition to provide a unit which is tough, tear-resistant, durable and flexible. Preferably, the partition is made of a polypropylene composition. Other suitable thermoplastic compositions which may be used are essentially polyethylene, polystyrene, polyvinyl chloride, copolymers of vinyl chloride and vinyl acetate, or a polyamide (nylon). The unitary, grille-like member, because it is molded, permits the product to be precisely dimensioned and contoured to closely match the configuration of the luggage case with which it is to be assembled, thereby complementing the radii defining the internal contours of the case. It is contemplated that the grille-like partition also may be made by stamping a sheet of plastic material of suitable thickness.

40 The grille-like member provides a network of spaced, integrally connected, intersecting, narrow strips, webs or rods of the plastic material. Preferably, the space strips lie in and intersect one another in substantially the same single plane, and the periphery of the network is circumscribed or defined by a continuous, narrow strip, also in the same plane, which furnishes the exact, desired peripheral outline of the network constituting the grille-like partition. The grille-like partition is formed to provide integral means for hinging the partition to the luggage case. Also, the partition is formed with integral means for connection of the partition to the turnbuttons. In the preferred embodiment of the invention, the partition also is made to provide, as an integral part thereof, supporting means for pocket members.

In greater detail, reference is made to FIG. 1 which illustrates a partition A made in accordance with the invention in assembled relationship with a luggage case B. In the illustrated embodiment of the invention, the case is generally of rectangular shape. It will be understood however, that it is within the scope of the invention to provide a case of circular or other desired contour, whereupon the cooperating partition is made to provide a matching or like peripheral outline. The case may be of the hard variety or molded of plastic material, or it may be of leather, or leather-like flexible wall material.

The luggage case shown comprises a pair of case halves or sections 20 and 22 hinged to one another by a pair of laterally spaced hinges 24 and 24'. The case section or lid 20 is provided along its free peripheral edge with a male valance member 26 adapted to be received, when the case is closed, in a channel or female valance member 28 secured to the peripheral edge of the case section 22. The case section 20 is provided with a pair for laterally spaced hasps 30 and 30' for cooperation with locks (not shown) on the opposite case section 22. The case section 20 also has secured thereto a pair of laterally spaced turnbutton assemblies 32 and 32' for cooperation with the partition A so that goods packed in such case section may be retained therein by the separable connection of the partition with the turnbuttons. The partition is hinged to the case section 20. The grille-like partition and the cooperating case section may be hinged to one another in any suitable manner. It is preferred however, that they be hinged connected in a manner to be subsequently described in detail.

FIG. 4 illustrates a preferred embodiment of the plastic, grille-like partition A. The partition is molded to provide a plurality or series of spaced, parallel strips 32 which extend across the width of the partition. Such series of spaced strips are intersected by a plurality of integrally connected, spaced strips 34, which preferably lie substantially in the same plane and extend substantially at a right angle to the first-mentioned series of strips, and thereby provide openings 36 extending through the partition. The strips may intersect one another at any suitable angle, and other than at a right angle, as shown. The number of intersecting strips and their spacing from one another depends upon the linear dimensions of the partition, which in turn is determined by the linear internal dimensions of the case half with which the partition is to be associated. The openings 36 provided by the network of spaced, intersecting, integrally connected strips may vary in size. The openings are made small enough to prevent apparel or like goods from extending an undue amount through the partition. On the other hand, the openings are made of a size sufficiently large to afford a substantial measure of flexibility, together with light weight and economy of material. The distance between the spaced strips may be on the order of approximately two inches in one direction, whereupon the distance between the strips angularly disposed with respect thereto may be on the order of approximately one inch. The extent of the spacing between the strips is a matter of choice, consonant with a suitable balance of the aforementioned factors. Preferably, a continuous or endless strip 38 extends around the periphery of the network to furnish a smooth or unbroken edge which defines the exact, desired outline of the partition.

In the particular embodiment of the partition illustrated in FIG. 4 (and FIG. 2), integrally connected strips 40 are located to extend intermediate and parallel to pairs of the spaced strips 32; also, a number of integrally connected strips 42 are located intermediate and parallel to pairs of strips 34. As shown, the strips 40 are not necessarily in linear alignment with one another, and the strips 42 also are not necessarily in linear alignment with one another. They may be arranged in linear alignment, or they may be laterally offset from one another, it only being necessary that the openings 36 bounded by the

spaced, intersecting strips be of suitable size. Each of the aforementioned strips 32 and 34 may also have portions of their lengths laterally offset from one another, though the strips lie in substantially the same plane.

The integrally connected strips 32, 34, 40 and 42, and the peripheral strip 38, are of relatively narrow width and thickness, or diameter. The strips of the network may be all of the same cross-section or they may possess different cross-sections. The strips may have a cross-section which is circular, elliptical, substantially rectangular, square or of any other desired cross-section. In the preferred embodiment of the invention, the intersecting strips 32 and 34, and the peripheral strip 38 are of identical cross-section and, as shown in FIG. 11, are contoured to provide a short, laterally extending reinforcing rib portion 44. The intermediate strips 40 and 42, which are of like cross-section, may be smaller in dimensional cross-section than the cross-section of the strips 32, 34 and 38 and possess a substantially rectangular cross-section, as also shown in FIG. 11. The molding of the partition permits variation of cross-sectional contour and cross-sectional dimensions of the strips to thereby furnish the desired degree of flexibility or stiffness at selected areas of the partition. Where, as in the illustrated and preferred embodiment of the invention, provision is also made for the support of a pair of pocket members by means of integrally formed panels which furnish a measure of stiffness at the areas where they are located, the areas adjacent the panels may be provided with the intermediate strips 40 and 42 of reduced cross-sectional dimensions to furnish a compensating measure of flexibility.

As previously indicated, the partition of the invention includes, as an integral part thereof, hinge means for connecting the partition to the luggage case. For this purpose, the peripheral strip 38 may be molded of circular cross-section throughout, or at selected sections thereof to provide laterally spaced hinge or pivot means 50 and 50' along the edge of the partition, as shown in FIG. 4. As also shown in FIG. 6, the longitudinal ends of each pivot or pintle section is confined by a pair of the laterally spaced strips 34 extending at a right angle to the pivot section. It is preferred that the integrally formed pivot portions 50 and 50' each be slightly offset to lie in a plane parallel to the plane of the network of spaced, intersecting strips for more convenient hinging of the partition to a partition hinge means about to be described. The offset relationship of the integral hinge means with respect to the adjoining portions of the partition is best illustrated in FIG. 12.

A preferred manner for hinged connecting the partition to the luggage case is illustrated in FIGS. 5 and 6, showing one of the pair of hinge arrangements. Each case hinge 24 has appurtenant thereto a partition hinge fitting 52. The partition hinge fitting is aligned with the case hinge 24 with its base portion 54 located on the interior side of the case section 20. Fastening means 56 is extended through the base portion 58 of the case hinge 24, an opening in the case wall and an opening in the base portion 54 of the partition hinge. A second fastening means in the form of a spaced headed rivet or nut, and short bolt arrangement (not shown) is used to secure the case and partition hinges 24 and 52 to the wall of the case to secure both hinge members against rotation. The partition hinge 52 is formed to furnish a springy, hook-like portion 60 providing an opening 62 having a height slightly less than the diameter of the partition's pintle portion 50. The resiliency afforded by the hook-like configuration permits the pintle portion 50, or 50', to be snapped beneath the bent over portion 60 for connection of the partition to the case. The described arrangement permits the partition to be separated from the case by the application of a force in the opposite direction.

As previously indicated, the partition of the invention also is provided with integral means permitting the sep-

arable connection of the partition with the turnbuttons on the laterally spaced turnbutton assemblies 32 and 32'. As shown in FIGS. 2 and 4, the partition is provided with a pair of laterally spaced openings 64 and 64' inward of the peripheral edge strip 38 and along the side of the partition opposite the side having the spaced hinge means 50 and 50'. The turnbutton openings 64 and 64' are each defined on one side thereof by the peripheral strip 38, on the opposite side by a strip of the network, in this instance, a strip 40, and on its other two opposing sides by short strips or webs, designated 66, 66' and 68, 68', respectively. The dimensions of each of the openings 64 and 64' is such that a turnbutton 70 may be passed therethrough with a slight amount of clearance, and upon rotation through a 90° arc will extend across the adjoining web material 66, 66', or 68, 68'. FIGS. 7 and 8 illustrate the manner in which the hinge partition is separably held to the lid section of the case to retain the goods therein.

While not essential to realize a number of the stated purposes and advantages of the invention, it is preferred to construct the partition so that it also functions to separably support a pocket member. For this purpose, the network of spaced, intersecting, integrally connected strips constituting the grille- or lattice-like structure may be provided with an integrally connected pocket-supporting panel or panels.

FIG. 4 shows a partition which is provided with a pair of pocket-supporting panels 72 and 74. As shown, the panel 72 has one edge thereof 76 integrally connected to a transversely extending strip 32 of the network. The panel, which lies in the same plane as the spaced, integrally connected strips comprising the grille-like network, has its other three edges 78, 80 and 80' unconnected or free and spaced a small amount from the adjacent strips. Similarly, the second panel 74, is integrally connected along one edge thereof 82 to another of the strips 32, and has its other three edges 83, 84 and 84' spaced from and free of adjoining strips of the network. This panel is also provided with a pair of laterally spaced notches 86 and 86' at the corners where the panel is integrally joined to the partition for cooperation with the particular kind of pocket member to be shortly described. Intermediate the width of the panel 72, below the free edge 78, and between a pair of spaced parallel strips of the network, a tab 87 having an aperture 88 is provided to bridge a pair of the spaced strips. Similarly, a tab 90 having an aperture 92 bridges and is connected to a pair of spaced, parallel strips below the central portion of the panel 74. The tabs are integrally formed parts of the partition.

For cooperation with and support by the panel 72, a pocket member P as shown in FIG. 9 is used. Such pocket member may comprise a pair of front and back walls 94 and 94' of equal linear dimensions which are joined to one another by an intermediate gusset 96 extending along the ends and bottom of the front and back walls, thereby leaving the pocket member open at the top. The parts of the pocket member may be connected to one another by sewing. The gusset is a flexible material or fabric which is unreinforced, whereas the walls 94 and 94' may be of cardboard covered with a fabric material to furnish relatively stiff sides. A loop 98 may be stitched to the front face of the wall 94 and a loop 98' may be stitched to the exposed face of the wall 94'. The gusset 96 has secured thereto the mating parts of a snap fastener 100, the male and female parts being secured in spaced relationship at the central, bottom side of the gusset, with the coacting male and female elements extending from the gusset's underside.

To separably secure the pocket member P to the panel 72, the panel is bent out of the plane of the partition about the hinge provided by the integral connection of the panel to the network at 76. The top open end of the pocket member is then slipped over the panel, and the

panel 72 is returned to its normal condition where it lies in the plane of the partition network. As shown in FIGS. 2 and 3, the snap fastener elements are connected through the opening 88 in the tab 87. As a result, and as shown in FIG. 3, a pair of compartments 102 and 102' are provided, one on each side of the partition panel 72. If desired, another tab (not shown) may be used to bridge the small opening between the lower edge 78 of the panel and the bottom wall provided by the connected gusset 96. A flexible strip of leather or leather-like material 104 is passed through an opening 36 at the upper central portion of the partition and around a strip 40 to provide a pair of strip portions 108 and 108', the strip portions being secured to one another beneath the fold by a rivet 110 extended through an aperture 36 on the other side of the intervening strip. The strip portions 108 and 108' are adapted to have the ends thereof extended through the loops 98 and 98' and provide a closure for each of the compartments 102 and 102'.

For the panel 74, a pocket member P' as shown in FIG. 10 may be used. Here, the pocket member is in the form of a continuous, endless band of flexible material 114, which may be formed by sewing the ends of a strip of textile fabric together at 115. One edge of the loop is connected, as by sewing, to an intermediate or bottom strip 116 of flexible fabric material. The opposite end 117 of the loop is left open. An elastic band 118 is sewn along the top edge of the loop, and an elastic band 120 is similarly sewn or connected to the lower edge of the loop, requiring the loop to be stretched to fit about the panel 74.

The pocket member P' is assembled with the panel 74 by bending the panel out of its plane where it normally lies in the plane of the partition, and slipping the stretched material over the panel through the top open end 117. The elasticity of the top band 118 pulls the ends of the pocket member into the notches 86 and 86'. The spaced elements of a snap fastener 124 secured to the flexible bottom wall 116 of the pocket member in the relationship previously described, are positioned on opposite sides of the tab 90, and snapped together through the tab's aperture 92. The panel 74 acts as a divider for the pocket member, and furnishes two separate compartments 122 and 122', as shown in FIG. 3.

It will be apparent that when either of the pocket members P or P' become soiled, one need only separate the snap fastener elements to enable the pocket members to be removed from the partition. In the case of the pocket member P', it is, of course, stretched to disengage the edge thereof from the notches 86, 86'.

It is believed that the advantages of the invention will be apparent from the foregoing detailed description and illustrated embodiment of a preferred form of the invention. The plastic grille-like partition is made to desired, exact size and contour in a single operation. The desired degree of flexibility may be provided at those areas of the partition where different measures of flexibility are desired. The partition may be twisted and bent in the normal use and abuse which a partition receives when the luggage case is packed and overloaded with unevenly distributed goods. As soon as the stresses are removed, the partition returns to its normally flat condition and peripheral outline conforming to the radii of the particular luggage case with which it is assembled. If for any reason the full height of the case is desired without any intervening partition, the partition conveniently may be removed and stored until the use thereof is desired, the separable hinge connection of the partition with the case permitting this purpose to be attained. The partition carries its own integrally formed hinge means allowing the separable connection of the partition to the luggage case. Additional components for this purpose and the assembly operation of such components to the partition are unnecessary. The partition also includes integrally formed eyelet means for cooperation with the turnbutton

assemblies. A pocket member or members may be quickly and easily assembled with the partition to afford a pair of compartments for each pocket. The pocket members may be easily removed and replaced if they become soiled, and it is desired to clean them. The plastic material of which the grille-like partition is made is not readily soilable, and if something is spilled on it, the nature of the plastic material is such that it will not stain and may be easily cleaned by simply wiping with a tissue or the like.

While a preferred embodiment of the invention has been illustrated and described, it will be understood that various modifications and changes may be made without departing from the spirit and scope of the invention as sought to be defined in the following claims.

I claim:

1. A flexible partition for luggage comprising a network of spaced, intersecting, integrally connected strips, said network being dimensioned and contoured to complement the internal contour of a luggage case, a panel integrally connected to a strip along a portion of its edge, the remaining edge portion of the panel being unconnected to the network, the strips and panel being formed of plastic material, and a pocket member supported by said panel with the panel received in said pocket member whereby two pockets are provided each having the panel as a wall thereof.

2. A flexible partition for luggage comprising a network of spaced, intersecting, integrally connected strips, a panel integrally connected to a strip along a portion of its edge, the remaining edge portion of the panel being unconnected to the network, the outline of the partition being defined by a continuous, peripheral strip integrally connected to the network, said peripheral strip being contoured to complement the internal contour of a luggage case, said strips and panel being molded of plastic material and normally disposed in a substantially common plane, and a pocket member supported by said panel with the panel received in said pocket member whereby two pockets are provided each having the panel as a wall thereof.

3. A flexible partition for luggage comprising a network of spaced, intersecting, integrally connected strips, a panel integrally connected to a strip along one edge thereof, the remaining edges of the panel being unconnected to the network, the outline of the partition being defined by a continuous, peripheral strip integrally connected to the network, said peripheral strip being contoured to complement the internal contour of a luggage case, said strips and panel being molded of plastic material and normally disposed in a substantially common plane, said peripheral strip providing pivot means for connecting the partition to a luggage case section, and a pocket member supported by said panel with the panel received in said pocket member whereby two pockets are provided each having the panel as a wall thereof.

4. A flexible partition for luggage comprising a network of spaced, intersecting, integrally connected strips, a panel integrally connected to a strip along one edge thereof, the remaining edge portion of the panel being unconnected to the network, the outline of the partition being defined by a continuous, peripheral strip integrally connected to the network, said peripheral strip being contoured to complement the internal contour of a luggage case, said strips and panel being molded of plastic material and normally disposed in a substantially common plane, said peripheral strip providing pivot means for hinging the partition to a luggage case section, the network providing an opening adjacent said peripheral strip on the side of the partition opposite the side where said pivot means are located, said opening being adapted to receive a turnbutton, and a pocket member supported by said panel with the panel received in said pocket member whereby two pockets are provided each having the panel as a wall thereof.

5. A partition for luggage as set forth in claim 2, wherein the strips of the network within the peripheral strip are of different cross-sectional dimensions at selected areas to provide areas of selectively different flexibility.

6. A partition for luggage as set forth in claim 2, wherein the partition is substantially rectangular in outline; wherein the network comprises a series of spaced, substantially parallel strips extending lengthwise of the partition and a series of spaced, substantially parallel strips extending at a right angle to the first-named series of strips.

7. A partition for luggage as set forth in claim 3, wherein the pivot means comprises a pin formed integrally with the peripheral strip offset to lie in a plane parallel to the plane of the peripheral strip.

8. A partition for luggage as set forth in claim 2, wherein the plastic material is selected from the group consisting of polypropylene, polyethylene, polystyrene, polyvinyl chloride, a copolymer of vinyl chloride and vinyl acetate, and a polyamide.

9. A luggage case comprising a lid case section and a cooperating case section, a case hinge connecting said sections, a partition hinge fitting positioned on the interior of the case lid section in alignment with said case hinge means, said partition hinge fitting comprising a resilient hook-like member having a mouth opening smaller than the interior of the hook-like member and a common fastening means extending through the case lid section wall securing the case hinge means and the partition hinge fitting to the wall.

10. A luggage case comprising a pair of case sections, hinge means secured to one of said sections, a flexible partition comprising a network of spaced, intersecting, integrally connected strips, the outline of the partition being defined by an integrally connected peripheral strip contoured to complement the internal contour of the luggage case, said strips being molded of plastic material and disposed in a substantially common plane, said peripheral strip providing pivot means connecting the partition to said hinge means.

11. A structure as set forth in claim 10, wherein the hinge means is formed to allow the partition to be separably connected thereto.

12. A structure as set forth in claim 10, wherein the plastic material is polypropylene.

13. A luggage case comprising a pair of case sections, turnbutton means secured to one of said sections, a flexible partition hinged to a case section, said partition comprising a network of spaced, intersecting, integrally connected strips, the outline of the partition being defined by an integrally connected peripheral strip contoured to complement the internal contour of the luggage case, said strips being molded of plastic material and disposed in a substantially common plane, the network providing an opening adjacent the peripheral strip for receiving said turnbutton means.

14. A luggage case comprising a pair of case sections, hinge means and turnbutton means secured to opposite sides of a case section, a flexible partition comprising a network of spaced, intersecting, integrally connected strips, the outline of the partition being defined by an integrally connected peripheral strip contoured to complement the internal contour of the luggage case, said strips being molded of plastic material and disposed in a substantially common plane, said peripheral strip providing pivot means connecting the partition to said hinge means, said network providing an opening adjacent said peripheral strip on the side of the partition opposite the side where said pivot means is located for receiving said turnbutton means.

15. A structure as set forth in claim 14, wherein the hinge means is formed to allow the partition to be separably connected thereto.

16. A structure as set forth in claim 14, wherein the strips of the network within the peripheral strip are of

different cross-sectional dimensions at selected areas to provide areas of selectively different flexibility.

17. A structure as set forth in claim 14, wherein a panel is integrally connected to a strip along a portion of its edge, the remaining edge portion of the panel being unconnected to the network to provide a panel having free sides, and a pocket member supported by said panel with the panel received in said pocket member whereby two pockets are provided each having the panel as a wall thereof.

18. A structure as set forth in claim 14, wherein the plastic material is polypropylene.

19. A structure as set forth in claim 14, wherein the pivot means comprises a pin formed integrally with the peripheral strip offset to lie in a plane parallel to the plane of the peripheral strip.
